United States Patent Office

THOMAS J. HALL, OF BRYAN, TEXAS.

Letters Patent No. 95,338, dated September 28, 1869.

IMPROVEMENT IN CULTIVATORS.

The Schedule referred to in these Letters Patent and making part of the same.

To all whom it may concern:-

Be it known that I, THOMAS J. HALL, of Bryan, in the county of Brazos, and State of Texas, have invented a new and improved Cultivator; and I do hereby declare that the following is a full, clear, and exact description thereof, which will enable others skilled in the art to make and use the same, reference being had to the accompanying drawings, forming part of this specification.

The object of this invention is to provide improved arrangements of means for adjusting the cultivators mounted on wheels, and provided with a seat for the attendant, whereby he can, when riding thereon, adjust them both vertically and laterally, for the control of the same.

Figure 1 represents a longitudinal section of my improved cultivator, and

Figure 2 represents a plan view of the same.

Similar letters of reference indicate corresponding parts.

The cultivator-beams A are connected rigidly together in pairs, and the beams of each pair are suspended at the front by adjusting screw-rods B, from the ends of short laterally-vibrating levers C, connected together in pairs, and vibrating from the centres D, where they are pivoted to the cross-bars E of the frame.

The front ends of these levers work between the cross-bars F, and have a slight vertical play between them on trunnions G, connecting them with the centres D.

Behind these centres the bars C pass under another transverse bar, I, and they are provided with springs

H, bearing up against the under side of the said bar I, imparting a yielding action to the said front supports of the cultivator-beams.

The rear ends of each pair of these springs have rods K, connecting them, and serving for the reception of the feet of the operator, sitting on the seat L, and by which he moves the said levers laterally, to guide the cultivator-beams.

The said pairs of beams are also connected, near the fronts, by draught-cords or chains M.

At the rear the beams are suspended by cords or chains N, from hand-levers O, working on joints P, having universal movements, which levers pass up in front of the seat, in a manner to be conveniently operated by the hands, for raising the said rear ends of the plow-beams, or guiding them laterally.

Having thus described my invention,

I claim as new, and desire to secure by Letters Patent—

1. The cultivator-beams A, arranged either singly or in pairs, and suspended, by the adjustable rods B, from the levers C, vibrating laterally, and arranged to be operated by the feet, substantially as specified.

2. The combination of the levers C, transverse beam I, and springs H, when arranged substantially as specified.

The above specification of my invention signed by me, this 28th day of June, 1869.

THOMAS J. HALL.
